UNITED STATES PATENT OFFICE.

EDWARD C. BAYNES, OF BUFFALO, NEW YORK.

DESIGN FOR A HEAD OR FOOT BOARD FOR METALLIC BEDSTEADS.

SPECIFICATION forming part of Design No. 26,596, dated February 2, 1897.

Application filed December 31, 1896. Serial No. 617,657. Term of patent 7 years.

To all whom it may concern:

Be it known that I, EDWARD C. BAYNES, a citizen of the United States, residing at Buffalo, in the county of Erie and State of New York, have invented and produced a new and original Design for Head and Foot Boards for Metallic Bedsteads, of which the following is a specification, reference being had to the accompanying drawing, showing a part thereof.

The single figure of the drawing shows the design as applied either to the head-board or foot-board of a bedstead.

The leading features of my design consist in the curved top rail C, which engages with the pillars A upon their outer sides, and the rods D, which extend inwardly and downwardly upon a compound curve and unite with the cross-rod B by means of a chill a, thus giving the said rods D the appearance of be-

ing continuations of the top rail C through 20 the pillars A. The other essential features are the vertical rod F and the curved rods E, which form an ellipse, the said vertical rod F and the said curved rods E uniting with the said top rail C by means of a chill b.

In the construction of full-width bedsteads I may add the curved rods D, engaging at their lower ends with the chill a and engaging with the top rail C by means of the chills c.

What I claim is—

The design for a head or foot board for a metallic bedstead, substantially as herein shown and described.

EDWARD C. BAYNES.
